William Debelleix Inventor
By his Attorney A. C. Van Dovenber.

UNITED STATES PATENT OFFICE.

WILLIAM DUBILIER, OF NEW ROCHELLE, NEW YORK, ASSIGNOR TO DUBILIER CONDENSER AND RADIO CORPORATION, A CORPORATION OF DELAWARE.

CONDENSER.

Application filed February 14, 1924, Serial No. 692,864. Renewed December 20, 1928.

My invention relates to condensers, and more particularly to variable condensers of the type used in radio communication.

An object of my invention is to provide 5 a condenser in which gradual adjustments of capacity may be effected with facility, and with a minimum of friction of the parts.

Another object of my invention is to provide 10 a condenser structure in which the fixed element is attached to the support in a simple, yet extremely sturdy manner, whereby the condenser may be capable of long continued use without fear of injury to the 15 fixed element.

A further object of my invention is to provide means for effectively preventing 20 displacement of the flexible element in the operation of the condenser, and also to provide a structure in which the movement of the compression plate for operating the resilient element is limited.

Yet another object of my invention is to provide 25 a construction having an easily formed and positively operable type of contact for making electrical connection with the movable element of the condenser.

With these and other objects in view which may be incident to my improvements, 30 the invention consists in the parts and combinations to be hereinafter set forth and claimed, with the understanding that the several necessary elements comprising my invention, may be varied in construction, 35 proportions and arrangement, without departing from the spirit and scope of the appended claims.

In order to make my invention more clearly understood, I have shown in the accompanying drawings means for carrying 40 the same into practical effect, without limiting the improvements in their useful applications to the particular constructions, which for the purpose of explanation, have 45 been made the subject of illustration.

In the drawings:—

Fig. 1 is a top plan view of my variable condenser;

Fig. 2 is a view in side elevation of the 50 form shown in Fig. 1;

Fig. 3 is a view in cross section, taken on the line 3—3 of Fig. 2, looking in the direction of the arrows;

Fig. 4 is a cross sectional view of my con-

denser taken on the line 4—4 of Fig. 2, 55 looking in the direction of the arrows.

In my invention, the fixed element comprises a sheet of metallic foil fixed to a suitable insulating support, the metallic foil being covered by an insulating sheet of mica 60 which extends beyond the edge of the foil, forming a projecting overlapping insulating sheet which prevents possible injury to the edge of the metallic foil. The metallic foil and the mica sheet are held to the support by means of eyelets which are passed through the support, the metallic foil and the insulating mica sheet, and are riveted in place to maintain holding washers in firm contact with the mica sheet. The resilient movable element of the condenser 65 comprises a bow or U-shaped metal strip, whose center is adapted to contact against the insulating mica sheet of the fixed element. A guiding yoke is attached to the 70 support for the fixed element, and prevents displacement of the movable element of the condenser.

Within the yoke is adapted to move a compression plate against which bear the 80 ends of the movable element. A reciprocating shaft operated by the movement of a screw within an operating knob causes the compression plate to approach or recede from the fixed element, thereby causing the 85 resilient movable element to be progressively laid down on and picked up from the surface of the fixed element. A U-shaped contact clip is adapted to contact with either edge of the resilient movable element to 90 make electrical connection therewith, in all adjustments of the condenser.

Referring to the drawings for a more detailed description, I have shown an insulating support 1, of bakelite or some other suitable insulating material. Fixed to the support 1 at its under side by some suitable adhesive is a strip of metallic foil 2, and overlying the metallic foil 2 is an insulating sheet of mica 3 whose edges project beyond 100 the edges of the metallic foil to protect it from injury; see Fig. 2. Passing through the support 1, the metallic foil 2 and the insulating sheet of mica 3 are eyelets 4. The eyelets 4 are inserted through the various layers, and holding washers 5 are slipped over the eyelets so that when the eyelets are 105 riveted in place, the holding washers 5

firmly hold the mica sheet 3, which is preferably also adhesively attached to the metallic foil 2, against the metal foil and the whole against the support 1.

5 The metallic foil 2 and the mica sheet 3 comprise the fixed element of my condenser. To make electrical connection with the fixed element, I have provided a binding post 6. Over the head of the binding post is passed

10 a contact washer 7 which is pressed against the metallic foil 2 through an aperture 8 cut in the insulating mica sheet 3. The end of the binding post 6, which projects upwardly through the support 1, is screw-threaded.

15 Electrical connection is adapted to be made to the binding post by placing a wire terminal between the metallic washer 9, and a nut 11 carried by the binding post 6. By tightening the nut 11, a terminal wire may 20 be firmly held in position.

Fastened to the support 1 by means of screws 12, is a yoke 13 of insulating material having downwardly depending parallel sides 14, which project below the fixed element of 25 the condenser. The yoke 13 is formed with a protruding central support 15. The sides 14 have cut out portions 16 therein, which lightens the construction. Passing through the depending parallel sides 14 are stop bars 30 17, comprising bolts which pass through from one side to the other, and are held in place by means of nuts 18. The stop bars 17 act to limit the movement of the movable element of the condenser in its minimum setting, as will be hereinafter explained.

35 Adapted to contact at substantially its middle point against the insulating mica sheet 3 of the fixed element of the condenser, is a flexible resilient metallic strip 19, of 40 U, or bow shape. The free ends 21 of the strip 19 bear against and are adapted to slide upon a metallic compression plate 22, which is affixed at substantially its middle by means of a screw 23 to a reciprocable shaft 45 24. Downward movement of the compression plate 22 is limited by the stop bars 17.

The reciprocable shaft 24 passes through an aperture 25 formed in the resilient metallic strip 19 that operates as the movable element of my condenser. There is an opening 50 26 formed in the mica strip 3 of the fixed element, and an opening 27 formed in the foil 2, to permit the passage of the reciprocable shaft 24 through the fixed element of 55 the condenser. The reciprocating shaft 24 passes through an opening 28 formed in the support 1, and an opening 29 formed in the support 15 of the yoke 13. The aperture 27, formed within the foil 2, causes the foil 60 to clear the reciprocating shaft 24 by a substantial margin, to prevent any possibility of electrical contact of the foil 2 with the shaft 24.

The support 15 is provided with an annular flange 31. Lying on top of this annular

flange 31 is a metallic washer 32 which is depressed at 33 into a depression formed in the upper surface of the support 15. This prevents the washer 32 from rotating. The washer 32 is provided with a tab or lug 70 34 which fits into a slot 35 formed within the shaft 24. The tab 34, by reason of its engaging the slot 35, prevents possible rotation of the shaft 24.

Mounted over the support 15 and having 75 its lower surface contacting with the washer 32 is an operating knob 36 of insulating material. The knob 36 is provided with an inner metallic hollow member 37 which is keyed to, or fitted tightly into, the operating 80 knob 36, and is adapted to rotate with the knob. The metallic hollow member 37 is provided with internal screw-threads 38 engaging with screw-threads 39 formed on the reciprocating shaft 24. To hold the operating knob in operative position, I have provided a U-shaped holding piece 41 of resilient metal, which engages the flange 31 formed on the upper end of the support 15, and likewise engages a flange 42 formed on 90 the lower end of the operating knob 36.

The U-shaped holding piece 41 holds the operating knob in operative position. To hold the U-shaped holding piece 41 in place after being fitted over the flanges 31 and 42, 95 I have provided a bolt 43 which passes through the free ends 44. A nut 45 holds the bolt in place and prevents the U-shaped holding member 41 from slipping from the flanges 31 and 42, though it is to be understood that the holding member is not so tightly adjusted as to prevent free rotation of the operating knob 36.

Upon turning the operating knob 36, the screw-threads 38 engage with the screw-threads 39 of the reciprocating shaft 24 and feed the shaft either in an upward or downward direction. The tab 34 on the washer 32, by engaging with the slot 35, prevents possible rotation of the reciprocating 110 shaft 24.

To make electrical connection with the movable resilient member 19, I have provided a U-shaped metallic strip 46. The strip 46 comprises a piece of spring metal 115 having downwardly projecting arms 47 which are adapted to fit over the yoke 13 and the support 1, and fit into two opposite openings 16 formed in the downwardly depending parallel sides 14 of the yoke 13. 120 The downwardly projecting arms 47 are inwardly intentioned, as indicated at 48, to make them project inwardly beyond the line of the inner surface of the depending sides 14.

125 Arms 47 engage and contact with the metallic compression plate 22, which, by reason of its sliding contact with the ends of the resilient U-shaped condenser member 19, is in electrical contact with that con- 130

denser element. Electrical contact is thus maintained at all positions of the condenser between condenser element 19, compression plate 22, and the arms 47 of the U-shaped 5 metallic strip 46. The strip 46 is held in place on the yoke 13 by means of a binding post 49, whose head 51 is countersunk in the under surface of the yoke 13. The upwardly projecting end 52 of the binding post 10 49 is screw-threaded, and a nut 53 operates on the screw-threads. Electrical connection may be made, through a proper terminal, with the movable element of the condenser, by placing a terminal wire between the strip 15 46 and the nut 53 and tightening the nut.

In operation, by turning the operating knob 36, the reciprocable shaft 24 may be raised or lowered to raise or lower the compression plate 22, which causes the resilient 20 U-shaped movable element of the condenser to be laid down on or picked up from contact with the fixed element of the condenser, thus varying the capacity. The maximum capacity is attained when the compression 25 plate is at its utmost upper position. The minimum capacity of the device is attained when the compression plate is arrested by the stop bars 17.

The resilient movable element 19 of the 30 condenser is prevented from becoming displaced and affecting the operation of the condenser by reason of the downwardly depending sides 14 of the yoke 13. Should the condenser element 19 slip slightly to one 35 side, it can go no further after it contacts with the inner surface of the downwardly depending sides 14. The stop bars 17 prevent possible movement of the compression plate 22 below the lower ends of the sides 40 14 of the yoke 13, and hence the condenser element 19 can not slip out of place.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from 45 the spirit of the invention, or exceeding the scope of the appended claims.

In Figure 2, the mica, and adjacent parts 14 are shown broken away to disclose the hole 8.

55 I claim:—

1. A variable condenser comprising a fixed electrode, dielectric material adjacent said electrode, a resilient electrode of opposite polarity adapted to be flexed into contact with the dielectric material by movement of its ends, and a guiding means for the resilient 60 electrode.

2. A variable condenser comprising a support, an electrode of one polarity, dielectric 65 material adjacent said electrode, a resilient

electrode of opposite polarity adapted to be flexed into contact with the dielectric material, and means attached to said support for guiding the resilient electrode.

3. A variable condenser comprising a support, an assembly including a fixed electrode and a dielectric member secured to one side of the support, a U-shaped resilient electrode of opposite polarity adapted to be flexed into contact with the dielectric member by movement of its ends, a guiding yoke for the resilient electrode attached to the support, a compression plate on which said ends of the resilient electrode bear, and tension means to pull the compression plate towards the 80 fixed assembly.

4. A variable condenser comprising a fixed electrode, a resilient electrode of opposite polarity having movable ends, dielectric material interposed between said electrodes, a 85 yoke for guiding said movable ends, means for making electrical connections with the fixed electrode, the movable ends contacting with the compression plate, and means for forcing the compression plate toward the 90 fixed electrode.

5. A variable condenser comprising a fixed element, a resilient movable element, a compression plate, a yoke for guiding the movable element, means for making electrical 95 connection with the fixed element, a plurality of metallic strips bearing on the edge of the compression plate to make electrical contact therewith, and means for flexing the resilient element.

6. A variable condenser comprising a fixed electrode, a resilient movable electrode, a compression plate on which the ends of the resilient electrode bear, a yoke for guiding the movable electrode, a U-shaped metallic 105 strip straddling the movable electrode and having both arms contacting with either edge of the compression plate, and means to flex the movable electrode.

7. A variable condenser comprising a fixed 110 electrode, dielectric material adjacent thereto, a resilient movable electrode having a central portion contacting with the dielectric material, and end portions adapted to be flexed into contact therewith, a guiding 115 means for the movable electrode, and means to limit the movement of said end portions away from the fixed electrode.

8. A variable condenser comprising a support, a fixed assembly including an electrode 120 and a dielectric member, a resilient electrode of opposite polarity adapted to be flexed into contact with the dielectric member by movement of its ends, and a guiding yoke for the movable ends fitting over the support and the fixed assembly, and means to limit the movement of the said ends away from the 125 fixed assembly.

9. A variable condenser comprising a support, a fixed plate of one polarity mounted 130

thereon, a U-shaped resilient movable plate of opposite polarity, dielectric material interposed between said plates, a compression plate on which the ends of the movable plate 5 bear, means for moving the compression plate towards and away from the fixed plates, a guiding yoke for the movable plate fitting over the support and the fixed plate, and means carried by the guiding yoke for 10 limiting the movement of the compression plate away from the fixed plate.

10. A variable condenser comprising a support, a fixed plate electrode mounted thereon, a U-shaped resilient movable electrode, a 15 compression plate on which the ends of the movable electrode bear, a reciprocating shaft passing through the support and attached to the compression plate, a screw means to re-

ciprocate the shaft, a guiding yoke for the movable electrode fitting over the support 20 and the fixed electrode, and means carried by the guiding yoke for limiting the movement of the compression plates away from the fixed electrode.

11. A variable condenser comprising a 25 fixed electrode, a resilient electrode of opposite polarity in spaced relation thereto and at one side thereof, the resilient electrode having movable ends, a reciprocating shaft, a plate operated by the shaft to flex the ends 30 of the resilient electrode towards the fixed electrode, an operating knob on the opposite side of the fixed electrode and operable to reciprocate the shaft.

In testimony whereof I affix my signature.
WILLIAM DUBILIER.
